Boyd (Reilly)

The Schedule referred to in the Gellat Patent and making part of the same, containing a description in the words of the said Boyd Reilly himself of his improvement in apparatus for applying either simple or medicated vapour or steam to the surface of the human body, being an improvement on his former Patent date February 5th 1831.

To all whom these Presents may come. Be it known that I, Boyd Reilly of the City of Philadelphia in the County of Philadelphia and State of Pennsylvania having obtained Letters Patent on the 5th day of February one thousand eight hundred and thirty one, for a new and useful improvement in apparatus for applying either simple or medicated steam to the surface of the human body, with perfect ease and safety in the chamber of the sick: having made considerable improvements in the same of which the following is a full and exact description. Note on figure A represents a machine which separates into three divisions, each part calculated to fit easily into the other, by which the length of the machine when packed up, is reduced nearly two thirds without a loss to the thickness. The top cover appears raised at the side, to show the three bows by which it is supported; the foot division is detached to show the fastenings by which it is united to the centre division; the false bottom is also detached, as it necessarily must be to permit the separation of the foot division. The shape of the frame is an egg oval at the head a full round, to accommodate the shoulders of the patient; at the foot made more acute for the convenience of packing up, also to afford as much swell as possible to the sides in order that the top and bottom covers may prop the frame. The dimensions of the frame are in length as follows: the head and bows are twelve and a

July 31, 1832

half that the center. The middle division is sixteen, & the fore division is sixteen and a half. The frame of the middle division is made of seasoned wood, with cleats to the side pieces of this frame, 4 inches in depth & $\frac{1}{8}$ of an inch in thickness; the length already given; they are bent round to the part of the coat they belong to a stretching rail of the same breadth and thickness is fastened into each end of the frame. The one at the upper end 25 inches in length, the one at the lower end twenty three, these stretching rails are hollowed out from the upper edge three inches in the center to make room for the body of the patient, they are glued in & further secured by a wooden pin passing through the same rails from top to bottom, that is 6 inches. The head division is formed by a piece of hickory or white oak (if green or well barked better) 4 inches in depth and three quarters of an inch in thickness, bent to the shape of the head of the frame on a block or form, after being prepared by barking or steaming, and then dried in the sun or with a fire to shape it in shape, the ends are secured by a stretching rail off of an inch in thickness, not to correspond in shape with the one in the middle division. The foot division is formed by a similar last piece made to the shape of the wide end of the coat & five eights of an inch in thickness. Stretching rail the same; these last pieces are fastened on the bottom edge between the same rails, to a half inch in thickness.

The patient's sedatives broad girth or "steaming web" as described in my former specification, down always in the division of it necessary in consequence of the division of the frame. This is shown on plate 100 figure 33. the buckles are made to receive the girth, when applied of an inch from the upper edge of the frame, it is to be observed that the girth is invariably turned from the inside of the frame without any form the buckles to be out to the breadth of the

7190X

July 31, 1832

27

girthings. The girthings being taken out whenever this machine is packed up, the ends are fastened with a strap and buckle of iron and half girthings or leather. They should be strong with buckles turned or plated, and attached by a strap to the frame. A piece of strong blanket 12 inches in breadth is extended along the centre of the girthings and fastened by the ends lapping under and taking a large horn button on the outer side of the frame. Two circular hollows are now to be made in beech wood one eighth of an inch deep the in the centre except at the head of the frame, where they should be gradually deepened to permit the piece that supports the cushion for the head of the patient to move upwards down; the use of other buttons being to secure the edges of the top and bottom covers. One of these hollows is a half eighth of an inch from the bottom of the girthings mortises, the other at the same distance from the lower edge of the frame. The upper edge of the frame and the girthings mortises must be made round and smooth so as to keep the girthings from chafing. The bottom of the middle division is covered with stout black hair turned close to the bottom on the sides but leaving a quarter of an inch at each end to cover the joints when the side divisions are attached; these projecting ends should be doubled, to give them strength and the cut edge should be varnished under the frame to protect it from the action of the vapours. The head and foot divisions may be covered with a lighter hair as all unnecessary additions to the weight of the machine should be avoided; the bottom of the head division should be perforated with twelve half inch holes one inch apart, close to the inside of the head of the frame, these holes are to permit the escape of the vapours between the bottoms; the two bottoms are fastened on with four and twelve which should be turned. The frame and bottoms should be painted with some strong colour not extractable from water.

July 31, 1832

The head division are attached to the middle division by strong wrought iron bolts, riveted into plates of stout sheet iron, the long or neck end being made square in order to prevent its turning; the plates with the bolts attached, are let into the stretching rails of the end division side inwards from the ends or outside of the frame. As near to the lower edge as the strength of the plates will admit of, as the pushing when pressed by the weight of the patient, draws the joints above; these plates are secured by a stout flat headed screw at each corner; the bolts should not project more than five eighths of an inch from the plates, lest they should penetrate thre' the opposite stretching rail and be exposed to the vapors. These bolts are received by similar stout iron plates let into the opposite stretching rail; and when the bolt at the bottom is pressed, after it has entered the plate, these fastenings should be well turned. The bars which support the top cover, are made of hickory or white oak, they are made round and half an inch in diameter, the bar for the head must not exceed the length of the middle division, as it must be packed up inside of the case. It is fastened by passing ^{the ends,} which should taper a little, thre' the two stretching rails, nearer the head and close to the inside of the head division. Which will cause it to be let into the side of the middle division one eighth of an inch being the difference in thickness; the holes are bored thre' the stretching rails in such a direction as to elevate the center of the bar 17 inches above the top of the frame; the center of the bar should stand in line with a line that would be perpendicular to the outside of the head of the frame. The center bar is like the head bar in shape, but wider in span as occupying the widest part of the frame; it hangs on the top stretching bar with the head and foot bows; it is placed at the upper end of the center pushing member and not at the lower end, necessarily marked on the

July 31, 1832 39

americana) it is fastened by being let into the side-pieces and
quicker than such the bottom of having them. the side is written
in one end of the bottom; a thin plate or half-circular frame
conceals the ends and is fastened on with two locks.

The foot bow is bent to the shape of the foot of the machine, for-
merly like the hand bow, is elevated 16 inches from the top of
the frame and stands 44 inches from the suspension line.

which permits the cover to be put on and taken off with more
ease.

The head of the patient rests on a circular board, 6 inches
in diameter, covered and softly stuffed with wool or curled
hair; a lace socket is fastened on the bottom of the board one
inch from the edge, this socket is one inch and half in di-
ameter and is made to receive the end of a sliding stock 11 inches
in length, one inch and a quarter in breadth and five eights
in thickness, rounded on one side to a half circle the flat side
rests against the head of the machine and is kept in its place
by a trap socket, fitting round it & fastened with screws to the
head of the frame; a short thumb-screw is let into the center
of the socket which keeps the cushion elevated or depressed
at the pleasure of the patient. This fastening will be better
understood as the ~~farmer's~~ fastening of a barker's chair;
it is much more simple and cheap than the one on my
model. The best material I have found for the cover, is
light curled muslin, it should be stitched on a frame the
width side with in or from you a coat of white wash laid
on first, made of good Spanish whitewash, and of such a consist-
ency as not to run thro' the object of this fastener, having
to prevent the preparation hereafter mentioned running thro'
before the white wash has time to dry, follow with a layer of
the following preparation. In the manner described in my first
specification with some other sufficient to give it a smooth
body and so strong however as if you common paint. Lay on a
sufficient number of coats to close up the pores of the skin.

July 31, 1832

which can be concealed by holding it against the light. It should three quarters of a yard wide in the bottom breadth. When it is thoroughly dry it should be passed round the frame secured at the head and foot and third the centre; if an outer cover is used the same may be on the outside; the cover should fit easily as it will shrink a little; the lower edge of this cover is secured by a stout cord such as that used for sack weights. It should be well stretched, a leather strap sewed at one end and a three quarter rotten buckle to the other. The cord is passed loosely into the edge of the cover the strap and buckle at the foot. The centre of the cord must fast at the centre of the head. This cord draws the edge of the cover into the circular hollow already described.

A circular hole 12 inches in diameter, is cut in the centre of the head of this cover, a leather strap of the same diameter one inch in breadth with a stout wire in each edge to keep it from slipping is secured in this opening by a band made of a single thickness of strong silk or cloth. which is covered with silk or thrillslein and one edge sewed round the opening. The other edge in which is a drawing string. is passed thro' the buckle & being retensioned on the outside is drawn tight with the string, the band being made just deep enough for this purpose which will be about one inch and a half. This tie strap also covers the edge of a bag which is placed round the neck of the patient and described in my first eight. For the folding portable machine. this top cover should have an outer cover of either a some light worsted fabric, or being folded up while warm it may adhere together. The false bottom is made of the painted Muslin cut to the shape of the bottom, otherwise being made for the same. it has a border two inches wide or deep, in the narrowest part but widening gradually towards the foot, in order to cover the end of the slope paper. A narrow oval hole is cut in the border on one side of the centre of the foot, so as to be out of the way of the paper from the former, and

7190X

July 31, 1832

11

hamy with a drawing string, is placed round the edge of this hole to secure the end of the escape pipe in the same manner as the tin hoop is described above. The escape pipe is made of three pieces of tin 12 inches in length, fitting one with in the other so as to occupy only the space of one; and sufficiently tapering to keep them from separating when drawn out; the smallest end of this pipe should be double the capacity of the pipe which admits the vapour. This end should be flattened to a oval form of about an inch across, so as not to cut away too much of the border of the false bottom, the end of this escape pipe is put up the chimney of the fire chamber. It is kept up against the back of the chimney by a double string which is fastened to the outside of the top cover of the pent, a ring or loop being fastened to the outer division of the escape pipe to receive this string. It should have been observed that the upper edge of the false bottom border has a small strap & buckle sewed in it like the top cover. The manner of raising the vapour is described in the first specification, the folding portable apparatus however requires a few alterations. It is promised that the heating apparatus is packed up with in the frame, which is 14 inches in depth, therefore it must be put up in this space. The lamp is found to burn better with naphtha and pure alcohol, it should therefore have four sockets for wicks in the lid, the wicks large one in the centre, the other divided round it. These wicks should be always pressed out after using as they will not burn well. The lamp, including the lid, & wick sockets should measure 4 inches square in depth and be of capacity to hold a pint. The supports for the vessel containing the material to be raised instead of being riveted to the lamp, must be riveted to a band which fits round the top of the lamp, and rests on projections of the raised or elevated on the sides. These pieces should raise the before above the lamp one inch and half, to keep the upper frame

July 31, 1832

slipping off, they should be set off and turned square off, when the lamp is to be packed up, the rim or base is taken off the top of the lamp, and slipped on the bottom and then lowered inside of the box itself, so soon ason which contains the material to be raised in vapors, the breadth and depth of this vessel being regulated by the size of the lamp when this packed up. The cap under which the lamp be are placed is made tapering and divided in the center so that the upper division shall fit inside of the lower division and both be placed over the lamp be when packed up. The lower division of the cap is & sister division of that below to form with its depth, it is made of light sheet iron by process of burning by the solder, lined inside and has a handle riveted to the side, it stands on three feet, which raise it three inches from the ground, these feet are made of thick iron with the edges turned over to give them strength, they also turn up inside with a hinge, so as to preserve the depth of 4 inches, the upper division is made of tin, it fits over the lower division when the cap is used, but goes inside of it when packed up, for which purpose the cap is made just sufficiently tapering, it is four inches deep including the half inch projection on the top above goes into the pipe. The tin pipe which carries the vapors into the furnace is one inch wide quarter diameter, one foot in length, a joint in the middle with another sufficiently long to bring it nearly level, the end which goes into the foot of the furnace between the two bottoms, is flattened to half an inch, so as not to cut away the same too much, a thin plate receives it which takes the effect of the flame, the wood is cut away a little over this pipe, so that the heat may not touch it, this pipe is held in its place by a tin plate 4 inches long and one and half wide, the one of this plate is turned over this plate as the carries the plate to fit into the pipe, a similar plate goes over the end

July 31, 1832

113

of the pipe inside of the frame, & is fastened with turned locks; the pipe should project over this plate one inch to keep the bed gap from scratching the wood. The pipe is secured from being pushed out by a large plate somewhat longer than the frame which is fastened by four small wood screws.

The machine is prepared for use by first attaching the end dividers, putting on the false bottom, drawing the trap and buckle tight at the foot; then the four chairs under the joints, taking care not to put them under the bottom parties, then ^{the purpose of the enclosing edge} measure it steady, as they will contract. It is a good way to place the patient first, then lay the chairs. The centre of the girding should be marked, so that the ends may come out even. The girding should be tightened by degrees, like a sucking bottom cord; a strip of stout blanket 12 inches wide, goes on the centre of the girding from head to foot and is fastened by a stripe of narrow girding, and a large bone button sewed on the bottom of the blanket at both ends. The tie hook which is round the patient's neck should be fastened in its place in the cover, and the lower edge of the cover put in its place at the head of the machine, so that the cushion for the head of the patient may be screwed in its place. The cover is then ^{turnt} over on the floor at the head of the machine, until the hoops or bows are put in their places over the patient, where the cover is turned over the edges placed in the bottom; the trap and buckle drawn tight the bag which has been previously placed round the patient's neck is then drawn round the tie hook by fastening the drawing string carefully between the wire edges. The escape pipe is then attached and the lower tightened. Should the patient turn, it has better to turn off. Should the patient be so ill that his feet will come over the opening of the foot, he should be caused to separate them. The machine is prepared by having the feet straight except the rising of the bed.

July 31, 1830

divisions, place the covers ~~unless~~ unless packed up, as already described, inside of it; slip the cushion off the stick that supports it, place them both inside; the escape pipe also, after shoving the joints together; after which the putting ~~the~~ ^{it} in a little practice will soon make the packing up easy; the head division is then turned bottom upwards over all the hoop or bars laid on the top. The covers folded as thin as possible and laid between the bars. A tin flask containing alcohol may be fitted to one of the corners, a tin case which may be black japanned is fitted to it, a strong wire should go round the lower edge of this case, it has no bottom. The bottom of the middle division answering the purpose; the case is fastened on by two hoops ^{one} on each, which fit on a turned iron stick screwed into the lower edge of the middle division, the sticks have holes in them ^{one} which a spring key passes, which keeps the hoop in its place; these keys are fastened to the case with small chains.

Apparatus for Hospitals and families

For these purposes the machine need not take apart, they may be made with two pieces, of the same depth and thickness, as the head division, bent to the shape of the head and foot & left long enough to be joined at ^{each} side in the center by a clapped ^{one} & inches, the lapp, called by carpenters the dove tailed ^{one} joint is the (best) thin glue and screws; three stretching rails of the same thickness but coming no higher up than the putting mortises; one of these stretching rails let in one eighth of an inch in the center of the frame; each of the others midway between the centers, the ends, fastened by gluing and nailing this the sides; the false bottom may be fastened on the frame; the lamp shade without the morning lamp; the lamp shade not to much tapering nor to divide on the center, one for the feet to turn up, having a hinge, a projecting loop or turn back firmly

7190X

July 31, 1832

105

be fixed to the centre of each side; and the gathering mortises
as may be brought at last are made together and an
additional mortise cut on each side.

A fixed apparatus.

As shown on plate 2, it is an oblong frame 6 feet long
from out to out, by two feet six inches wide, & 5 inches deep;
the frame is made of two thicknesses of seven eighths white pine
slab glued together; the top and heart edge being carefully
put together, to keep it from springing; the circle round the
neck 14 inches in diameter; a projecting wooden rim
receives the bag round the neck. The rim projects one
inch, is three quarters thick, should be slightly hollowed on
the outer edge, to receive the drawing string and keep the
bag from slipping; the inner edge should be rounded
smooth. The bag should be increased in depth in propor-
tion to the increase of diameter; the head of the frame should
be carried up by a baulk two inches into the circle; the
rim separated accordingly to leave a space for the neck
depth through outfitting on the cover, & covering
or other receding 4 inches deep from the upper edge is put
round the frame, leaving an inch at the lower edge to form
ten a festoon or valance to. A ledge of the bag going three
quarters of an inch thick and wide enough to cover the
edge and project to form a moulding, is fastened all round
the upper edge of the frame and fitted of course at the
corners. The cover is circular, it may be covered a made
entirely of six 18 inches high from the straight line at the
ends; the ends of the cover made of seven eighths white pine
in two thicknesses the grain of inside thickness running
up and down; these ends connected by side pieces made
like the side pieces of the frame below, and secured at the
corners in the same manner. The circular top is covered
by slabs of half inch pine running from hand to hand;

July 31, 1832

The breadth of a whale will vary according to the size of the circle they cover; the edges, of course, turned so as to joint. A covering of strong leather is drawn over these strips glued together and painted on the outside, the whale top being neatly covered with any leather that the fancy may suggest. The escape of the gas is prevented by a cone groove the shape of which is given on the drawing, the cone is one inch wide and three eighths deep. The hollow is worked in the ledge on the upper edge of the frame, a pine tongue is fitted into this hollow. The upper part is then glued and the cover being immediately secured. When the glue dries, the cone will be exactly in its place; the whole lower edge of the cover including the cone, is covered with even soft cloth, and the cover is made fast when in use by two trap traps on each side made on the same principle as the trap of a trunk lock the trap being attached to the cover. The receiving plates let into the side of the frame. The drawing shows the top suspended by cords and counter weights. The cords pass over pulleys fixed directly over them in the ceiling & are then fastened to weights which are contained within four hollow pillars which support the canopy and curtains. The cover may be attached by hinges on the back parts like the lid of a chest. The bottom of this apparatus, is twenty six inches wide by sixteen inches long three on each side. The vapour is admitted thro' a thin pipe running up thro' the leg at the back part of the foot of the machine, the vapour passes out thro' both the legs at the head of the machine. These legs may be made of such pine & white pine, which will have a cavity of two inches; they are made big enough within one inch of the bottom & may have some small panels on the head of the leg that is worn. The apparatus stands on a flat frame to which a light, thin plate

July 31, 1832

form projects beyond the apparatus at the front side and at each end, so as to have room for a person to walk round, the distance is left to the back of the machine; the platform or treads to the wall or partition at the back side of the machine, having a space to pass behind and adjust the iron. The platform also assists in bracing the columns which sustain the curtains. The two legs at the head are attached to a wooden pipe of the same size which passes under the platform from the wall or partition in the rear to communicate with a chimney, or perpendicular front of some height out of doors, the tin pipe which runs from the leg at the foot of the machine passes by an elbow under the platform, & communicates with the furnace which may be in the cellar, or out of doors, should there however be a fire place in the room so situated as to answer, it will save trouble; The furnace is heated by charcoal which is burned in a small sheet iron stove, similar to that used by tin manufacturers to heat their soldering iron, a circular sheet iron stove is placed over this with a door large enough to receive a vessel containing the materials to be raised in vapor, this door will be prepared to be raised or lowered at pleasure so as to admit a greater or less quantity of air; a flange and short pipe is attached to the back of this stove or to the top of it, as the case may be, which communicates with the tin pipe already mentioned. The furnace of the charcoal stove has a vent back and not be permitted to enter the machine on account of the smoke. The patent receives on a frame made of two pieces of cherry or similar wood 6 inches wide and one inch thick, the length of the inside of the machine these pieces placed on edge on each side of the machine are secured by four stretching pieces of the same thickness and running up to a ring of quarter inch iron band and

7190X

July 31, 1832

finished like the edge of the apparatus last described. The stretching piece at the head and foot passed bunches from each end. The other two equally divided, the stretching pieces tightened so hallowed out to within one inch wide half of the bottom; this frame can be taken up so as to dry the girding after using. (Holes must of course be made thru' the true bottom to communicate with the legs that are used for the support, the bottom is made fast to the legs by sealing. These openings in the bottom are covered by a piece of tin at each end 6 inches wide and extending across the bottom, these pieces are edged with strong wire and punched full of holes, in the edge of one edge several hinge pieces are placed, which are fastened by lined nails or screws to the end pieces of the frame, so far up as to make the tin form an angle with the corners.

The head cushion and support of this apparatus are made like the best one on my model, the cushion may be made larger and turned with more taste, this apparatus is painted with ochre.

Portable Machine for the Hand
The bottom part is made of stout tin, it is two feet long by one foot wide and four inches deep, it has a stout wire in the edge turned on the inside, the lid or top is two inches deep and when closed lays over the bottom one inch and is fastened by two loops on each side like a committee, when it is on the top, is supported by a tight trap joint in each corner, similar to a rule which when struck falls towards the centre without the sides of the machine. The vapour is raised and conveyed off in the same manner as the portable machine for the body, the lamp cap pipe is gradually made smaller, the vapour is admitted when a funnel is held close to the bottom at the end of the machine off

7190 X

July 31, 1832 49

site to where the hand is admitted, a flat slipper or baggage, six inches wide and half an inch high, is placed on the bottom from this side to the front of the machine, a range of small holes are punched in the half inch edge of this baggage by which the vapour is spread thro' the machine without carrying in a body in contact with the hand by which it might be scalded.

When the machine is in use a space of 12 inches is preserved by the outer joints between the edges of the top and bottom; the vapour is confined by an oil cloth prepared in the same manner as the cover of the portable box; while a circular opening is made in the end 16 inches in diameter; the bottom of the circle being even with the edge of the bottom, to the edge of which a bag is sewed, similar to those put round the neck of the patient in the other machine, like that last no folds round the hand and secured by a handkerchief. This oil cloth is secured at the bottom by being tucked round the outside of a wooden frame, which is made of pieces one inch wide and half an inch thick; these pieces are fitted (with their edges up and down) to the inside of the bottom; allowance being made for the thickness of the oil cloth and for pieces of the same breadth (one inch) and the thickness of the wire projecting on the inner edge of the bottom.

This frame is double tacked at the corners and fastened by round headed screws, which fasten the sides and ends thro' the filling of strips the thickness of the wire already mentioned into the frame, the lower edge of which is one inch from the bottom, and half an inch from the baggage which receives the vapour, the top edge of the oil cloth is tacked to the edge of a frame of the same breadth and thickness, which is fitted up flat against the inside of the top of the box in such a way and fastened

7190x

July 31, 1832

and with several headed screws these the top of the frame is lighter half and half at the corners all screws having to be made for the thickness of the iron or steel plate as the stiffening wire here is on the out side of the iron.

The escape pipe is made in joints and goes into the back part of the oil cloth, over the furnace pipe and close to the upper edge of the bottom screen in the same manner as that of the large machine. A handle is fixed in the center of the top. A support for the iron is made of short iron attached by a hinge to the wire in the edge of the bottom, and under the opening for the limb, this support may be 8 inches long and 4 wide; be stuffed on the top, and turned inside of the machine when closed up; a cushion covered with oil cloth is also made for the heel to rest on, it is attached to a tin stand in the form of a stool; the feet going on each side of the vapour receiver, and one inch high, which keeps it half an inch from the hot pipe. The inside well painted with ochre the outside black japanned. The machine rests on two thin wires.

Preferences to improvements.
